UNITED STATES PATENT OFFICE.

ERNEST E. WERNER, OF ST. LOUIS, MISSOURI.

APPARATUS FOR THE TREATMENT OF GASES BY ELECTRIC DISCHARGE.

1,363,827.

Specification of Letters Patent. Patented Dec. 28, 1920.

Application filed March 4, 1920. Serial No. 363,213.

To all whom it may concern:

Be it known that I, ERNEST E. WERNER, a citizen of the United States, residing in the city of St. Louis and State of Missouri, have invented new and useful Improvements in Apparatus for the Treatment of Gases by Electric Discharge, of which the following is a specification.

This invention relates to improvements in apparatus for the treatment of gases by subjecting them to the action of electrical discharges and has special reference to improvements in the type of apparatus shown in my prior Patent No. 777,987, dated December 20, 1904. The particular object of my present invention is to provide an improved airgap and closer regulation of the current passing through the airgap thereby producing materially greater efficiency both as regards the current consumption as well as the yield of the resultant gas.

The patent above cited deals with the formation of disruptive electrical discharges across an airgap and the injecting of gas under pressure into the gap transversely to the normal or direct course of the arc, thereby deflecting the discharge from such course and elongating it in a lateral direction; and by varying the pressure of the gas so injected correspondingly varying the extent of such deflection and elongation of the arc and thereby regulating the volume or surface of the discharge to which the gas is exposed.

The efficiency of this device, while fully substantiated in commercial practice, is somewhat low, and I have ascertained by experiment that by using the arcing unit of the present application a very material increase of efficiency can be brought about.

As is well known, the efficiency of apparatus of this type, used most generally in the fixation of atmospheric nitrogen, depends, first, upon the maximum attenuation and nature of the arc or disruptive discharge; and, second, upon the power factor at which this attenuation is obtained, *i. e.*, the operating efficiency of the step-up transformer. Given the maximum attenuation the apparatus of course becomes, as regards the resultant gas, extremely sensitive and responds to minute variations of the inductance in the circuit. Such maximum attenua-

tion with the resultant efficiency referred to I secure in my present invention by the provision of a chamber of novel shape enclosing the electrodes and into which a blast of air is blown which in the normal course of its expansion would assume a shape which would approximate the inverted cross-sectional shape of the chamber into which it is discharged.

Figure 1 is an assembly of my improved arcng unit shown in elevation, a part of the casing being broken away to better illustrate the construction; Fig. 2 is a top plan view of the inductance coil shown in vertical elevation in Fig. 1; Fig. 3 is a section taken on the line 3—3 of Fig. 1 and viewed in the direction of the arrows; Fig. 4 is a top plan view of the air-nozzle; Fig. 5 is a vertical sectional view thereof on the line 5—5 of Fig. 4; Fig. 6 is a top plan view of a modified construction of air-nozzle; Fig. 7 is a vertical sectional view on the line 7—7 of Fig. 6; and Fig. 8 is a diagrammatic view illustrating the relative course, shape and action of the air blast in the arcng chamber.

Referring now to the drawing, the numeral 1 indicates a metallic supporting plate for the entire apparatus. Mounted on this plate are suitably spaced bosses 2, which in turn support a metallic plate 3, upon which is mounted a casing 4, providing a gas chamber. In this casing there is provided an observation window 5, through which the action of the discharge, to be later referred to, may be observed. The numeral 6, indicates a boss to which may be attached a pipe, (not shown) for carrying off the gas produced by the action of the apparatus. The numeral 7 indicates an elbow to which is connected a pipe 8 and a screw-threaded nipple 9, the latter having a smooth upward extension shown in Fig. 3, forming an air-nozzle 10. The numeral 11, indicates an insulating plate and the numeral 12 indicates a sleeve having a central screw-threaded portion 13, which is screwed into, and projects above, the insulating plate 11, said projecting portion receiving a nut 14, by means of which the sleeve 12 is held on the said insulating plate. The sleeve 12 is provided with a smooth bore which extends up through the screw-threaded portion 13, said

bore snugly receiving the air-nozzle 10 in such manner that the sleeve 12, with the plate 11 and the parts carried thereby, can be adjusted as to height on the air-nozzle 10. A set screw 15 holds the sleeve 12 in adjusted positions on the air-nozzle 10. Mounted on either end of the insulating plate 11 are metallic supports 16, each of which comprises a lower rectangular portion 17, Fig. 3, and a central upwardly projecting tapering portion 18. Adjustably mounted in each of the supports 16 is an electrode 19, the said electrodes being adjustably held in the supports by means of set screws 20. Each of the electrodes 19 has an angularly disposed arm 21, said arms converging toward the top of the air-nozzle 10, their arcing points 22 terminating directly above the orifice of said air-nozzle. Mounted on the top of the rectangular portion 17 of the supports 16, on either side of the central projecting portion 18, are spring clips 23, which normally tend to press against the sides of the projection 18, and are held on the base portion 17 of the support, by means of insulating strips 24, which rest upon lower bent portions of said spring clips, as shown in Fig. 3, and screws 25 which pass through said strips and into the base portion 17. The numerals 26 indicate two plates of mica, or similar material, such as fused silica, which are inserted at either end between the projection 18 and the spring clip 23, and converge upwardly leaving a narrow slit or outlet slot 27 between their upper edges. It will be seen that the plates 26 with the projections 18, against the sides of which the plates 26 are pressed, at their ends, by spring clips 23, form a triangular-shaped chamber inclosing the electrodes 19, and into the bottom of which the nozzle 10 projects, said chamber, however, being open at its bottom. The numerals 28, Fig. 1, indicate connecting screws which serve to attach the secondary terminals 29 of a step-up transformer 30 to the metallic supports 16, the said terminals passing upward through insulating bushings 31, mounted on the plate 3. In this way the electrical connection is made with the electrodes 19. The numeral 32 indicates the primary winding of the said step-up transformer, to which is connected, in series, an inductance 33 by means of wire 34, which wire, after passing through the said inductance, returns by lead 35 to the terminal 36 of the circuit. The numeral 37 indicates the other terminal of the circuit which, with the terminal 36, serves to connect the entire apparatus, to a suitable source of alternating current (not shown). The inductance 33 has the ordinary laminated construction of an iron core with two legs, and upon the upper ends of the legs of this core are mounted laterally adjustable slides

38, Fig. 2, which are clamped into position by means of clamps 39, bolts 40 and nuts 41. As will be seen, these slides are of the same width as the legs of the core and have sufficient movement to either maintain the maximum air-gap between the legs, thereby making an open magnetic core construction, or to be brought together to make the device virtually a closed magnetic circuit. The slides 38 are also of laminated construction, the laminations being held together by brass plates 42, insulated bolts 43 and nuts 44, and are movable laterally in slots 46, whereby, as stated, they may be separated or brought together. As will be seen, the lines of force, passing through the winding of the inductance, or choke coil, 33, may be widely varied without opening the electrical circuit. By means of this design I am able to decrease the current passing across the arc between the points 22, from 50% to 60% of the maximum. Referring now, particularly to Figs. 3, 4, and 5, the air-nozzle 10 is shown to have a slotted orifice 47 in its upper end. The walls of this slot diverge slightly so that the air blast passing therefrom, if unrestricted, would be triangular in cross-section, as indicated by the dotted line 48. This air blast, however, impinges at 49 (see Fig. 8) upon plates 26 and forms a peculiar air vortex which is diagrammatically illustrated in said Fig. 8. By loosening the set screw 15, the electrodes 19 may be adjusted toward and from the outlet 47 of the air-nozzle as occasion may require. The air-nozzle of Fig. 3 is shown in plan view in Fig. 4 and in section in Fig. 3. In Figs. 6 and 7 a modification of this air-nozzle is shown in which, in lieu of the transverse slot 47, I employ a series of apertures 50, arranged transversely of the air-nozzle, and each of these apertures is, or may be, slightly tapered inwardly, as shown by Fig. 7, in the same manner as the slot 47 is tapered. In either form of air-nozzle, the air discharged from the outlet will, as heretofore mentioned, impinge upon the mica, or other plates 26, at points 49 midway of the height of said plates, as indicated in Figs. 3 and 8. As shown by the latter figure the air will tend, after contact with the plates 26, to pass up the inner walls thereof and out through the opening 27 at the apex formed by these plates. Between these plates 26 which have an angular disposition with upward convergence, the air is expanded in a jet having a similar angular section inverted, which, of course, is accentuated by the flaring shape of the outlet 47. Thus it will be seen that the diverging air blast and the converging plates 26 form, as it were, two triangles extending in opposite directions and having a common base extending through the points 49 and forming a chamber in the lower of which the discharge from the electrodes is 130

surrounded by a film of air, while in the upper triangular chamber it is exposed to the bombardment of the converging streamlets of air. In other words, in the air chamber of the lower triangle the arc is merely attenuated and is forced by the air blast into the upper zone of maximum action.

As shown by Fig. 1, the ends 22 of the electrodes 19 are relatively closely connected 10 immediately above the outlet 47 of the air-nozzle 10, and diverge from this point upwardly. When the current is passing, an electric arc is established between the points 22. As the air passes out through the orifice 47 it diverges, as stated, its shape being fairly represented by the resulting flame indicated in Fig. 1 by the numeral 51, this flame being produced by the attenuation and spreading of the primary arc formed between the terminals 22 by the air blast. As will be seen the action of the air is peculiar 20 to the particular type of apparatus described. The air leaving the orifice 47 tends, as stated, to diverge or expand into the shape 25 of an inverted triangle until it engages the plates 26 at the points 49 where it still has considerable velocity, and at which points the flame has been already materially attenuated and passes upward from the points 30 49 to the outlet slot 27. Bombardment of the flame due to converging streamlets of air occurs, and a further sub-division and attenuation of the flame becomes so marked that it can be readily distinguished with the 35 naked eye. In addition aperture 27 still passing the air at some velocity narrows the flame transversely while it is at its maximum width, and the upward current of air through the outlet slot 27 still further 40 spreads the flame and facilitates exposure. The air and flame in their upward course pass through the opening 27 of the converging plates while still interacting. As heretofore stated, the efficiency of fixing atmospheric nitrogen depends to a far greater extent upon maximum attenuation of the arc than upon any other factor. The construction described above for attenuating and spreading the arc yields an efficiency which, 45 to my knowledge, heretofore has not been obtained at the same current consumption. For example, I have been able to obtain with an expenditure of 600 watts parallel, if not superior, results to those heretofore 50 obtained with the expenditure of over 2,000 watts in the use of my former type of apparatus referred to. If plates 26 be removed, the section of the flame becomes entirely different, representing now merely a 55 narrow cone no wider than the distance between the points 22. By the use, therefore, of the converging plates 26 having but a slight separation at the apex 27, and the consequent effect of the air jet discharged 60 into the chamber formed by said plates, I

secure a relatively enormous attenuation and spreading of the arc, the relative proportions of which I have attempted to indicate in Fig. 1 by the flame discharge 51, with resultant high efficiency in the production 70 of gas. Experiments have shown that the power factor of the transformer is materially and beneficially affected by the specific design herein described.

While the operation and effects of the adjustable inductance will be clear to those skilled in the art it may, nevertheless, be desirable to briefly indicate the action of this apparatus in operation. An alternating current of, say 60 cycles and 110 volts 75 being applied through terminals 36 and 37 and passing thence, as shown, through the inductance coils to the primary, induce in the secondary coil of the step-up transformer a current of high potential, say, 80 10,000 volts, and low amperage, which tends to establish a flaming arc across the spark-gap formed between the points 22. This 85 flame is of such temperature that, without the proper application of air, it would instantly fuse the silica or mica plates, such as the plates 26. With the air applied according to my novel design, however, a brilliant, 90 infinitely sub-divided, fan-shaped, disruptive discharge takes place of relatively tremendous area and of such low temperature that an ordinary match held above or within the flame will not ignite. To those skilled 95 in the art of chemistry the importance of this extremely low temperature within the 100 zone of the arc will be apparent as will be its relation to the efficiency of the output. Such low temperature is doubtless due to the fact that the peculiar angular air distribution within the chamber formed by 105 plates 26 and supports 16, precludes the formation of even minute flames or arcs, the electrical energy being almost entirely expended in the form of a disruptive discharge. Furthermore, as will readily be 110 seen, the air while exposed to the action of the active electrical discharge is always maintained at a pressure above atmospheric, and this appears to bring about a thermic balance tending to explain the extremely 115 low temperature existing within and above the zone of action.

The air-nozzle 10, which as stated may have either a single transverse slot lying parallel to the walls of the arcing chamber, 120 or a number of transverse tapered apertures, also extending parallel to the walls of the arcing chamber, produces a geometrical shape of the air jet which is the geometrical shape in cross-section inverted of the arcing 125 chamber itself. The transverse extension or length of the slot 27 forming the apex of the arcing chamber is also extremely important as a factor in widening the zone of reaction, *i. e.*, in producing the maximum 130

longitudinal dispersion of the flame with a minimum dispersion in a direction at right angles thereto.

I claim,

- 5 1. In an apparatus for generating gases from an electric discharge, in combination with an arcing chamber having upwardly converging walls, electrodes mounted therein and connected with a suitable source of electricity and means for directing a diverging blast of air upwardly between the electrodes, and against the walls of said chamber.
- 10 2. In an apparatus of the class described, in combination with an arcing chamber having upwardly converging walls, electrodes mounted therein and connected with a suitable source of electricity and means for directing a blast of air upwardly between the electrodes, such blast of air having a cross-section the shape inverted of said chamber.
- 15 3. In an apparatus of the class described, in combination with an arcing chamber having upwardly converging walls, electrodes mounted therein and diverging upwardly in the longitudinal plane of said chamber, means for producing an arc at the point of convergence of said electrodes and means for directing a diverging blast of air upwardly between the electrodes and against the walls
- 20 of said chamber.
- 25 4. In an apparatus of the class described, in combination with an arcing chamber having upwardly converging walls, electrodes mounted therein and connected with a suitable source of electricity and an air-nozzle having an outlet opening shaped to provide a blast of air of angular section corresponding to the similar shape, inverted, of the arcing chamber.
- 30 5. In an apparatus of the class described, in combination with an arcing chamber having upwardly converging walls, a pair of diverging electrodes mounted in said chamber and an air-nozzle having an orifice located below the converging ends of said electrodes and extending longitudinally of the electrode chamber.
- 35 6. In an apparatus of the class described, in combination with an arcing chamber having upwardly converging walls, a pair of electrodes mounted therein and diverging upwardly in a longitudinal plane of said chamber, means for producing an arc at the converging ends of said electrodes and an air-nozzle having an orifice located below the zone of said arc and extended longitudinally of said chamber.
- 40 7. In an apparatus of the class described, in combination with an arcing chamber having upwardly converging walls, electrodes mounted therein and connected with a suitable source of electricity and an air-nozzle

located below the arcing ends of said electrodes and having an orifice diverging outwardly and upwardly.

65

8. In an apparatus of the class described in combination with an arcing chamber having upwardly converging walls, providing a continuous opening at the apex, electrodes mounted therein connected with a suitable source of electricity, and means for directing a diverging blast of air upwardly between the electrodes and against the walls of said chamber.

9. In combination with a support, a pair of converging plates of mica, or similar material, mounted thereon providing a continuous opening at the apex, a pair of electrodes mounted in said chamber and connected with a suitable source of electricity and diverging upwardly over other arcing terminals in the longitudinal plane of said chamber, and an air-nozzle having an orifice located below the arcing terminals of said electrodes and diverging upwardly transversely of said chamber and extending longitudinally thereof.

75

10. In an apparatus of the character described, in combination with an arcing chamber, having electrodes mounted therein, means for producing a blast of air between the electrodes, and means for producing an arc between said electrodes, comprising an electric circuit including an inductance, the iron circuit of which is adjustable from a completely closed to a partially opened magnetic path.

80

11. In a device of the class described, in combination with the electrodes and means for producing an arc between the same, means for varying the arc comprising a choke coil having legs provided with slide members adjustable toward and from each other to vary the magnetic path.

85

12. In an apparatus of the class described, in combination with an arcing chamber having upwardly converging walls, electrodes mounted therein and connected with a suitable source of electricity, and means for directing a diverging blast of air upwardly between the electrodes and against the walls of said chamber whereby a zone of air blast is produced the lower portion of which diverges from the air-nozzle and is relatively quiescent and the upper portion of which is convergent and turbulent, the former condition tending to attenuate the arc and the latter to expose the attenuated arc to violent bombardment of converging streamlets of air deflected from the sides of the chamber.

90

110

13. In testimony whereof, I have hereunto set my hand.

ERNEST E. WERNER.
